UNITED STATES PATENT OFFICE.

GEARY E. CARSON, OF ALBANY, NEW YORK.

WINDOW-FASTENER.

1,307,112.

Specification of Letters Patent. Patented June 17, 1919.

Application filed July 24, 1918. Serial No. 246,441.

To all whom it may concern:

Be it known that I, GEARY E. CARSON, a citizen of the United States, and a resident of Albany, in the county of Albany and 5 State of New York, have invented certain new and useful Improvements in Window-Fasteners, of which the following is a specification.

My invention relates to improvements in 10 window fasteners, and, in the embodiment illustrated and described, is particularly adapted for the windows of railway cars, although it will be obvious to those skilled in the art, that it is useful in many situations and other connections.

In railway cars it is common to provide 15 a rack carried by the window frame and a latch carried by the window sash adapted to coöperate with one another so that the window may be fastened at various heights. It is customary to overhaul and refinish railway cars frequently and, in so doing, all fixtures are removed for the purpose of refinish- 20 ing, the metal fixtures being sent to a metal refinishing department for cleaning 25 and polishing, while the other fixtures, such as window sashes, are sent to another refinishing department for cleaning, revarnishing or repainting and the like. It is common to secure the racks and latches above 25 mentioned, in place by means of screws and consequently to remove them the screws must be removed, and after a number of such removals the screw threads become worn and 30 it is necessary to re bore and rethread the screw openings and to use large screws. Especially is this true in the modern steel car, where the sheet metal to which these parts are attached is very thin and the screw 35 threads therein easily become so worn as to be incapable of holding the parts in place. Furthermore, the removal of the numerous screws for the purpose above mentioned requires considerable time and labor which is 40 an important item of expense in the refinish- 45 ing of such cars.

The main object of the present invention is 50 to provide an arrangement by means of which such screws or bolts are avoided for securing these fixtures in place whereby the time and labor necessary to reborning and rethreading, where the screw threads have become worn out, is eliminated, and also by means of which these fixtures are very much 55 more quickly removed for refinishng there-

by saving a large amount of time and labor in the operation of overhauling for refinish- 60 ing. A further object of the invention is to provide arrangements by which such fixtures are also easily and quickly secured in place either at the beginning or after refinish- 65 ing. It is estimated that in an ordinary 70 foot car having forty-two double windows and two single windows, the labor cost of applying fixtures made in accordance with my invention will be only 20¢ as compared 70 with over \$4. for fixtures now commonly in use. And to remove the fixtures it is estimated that the fixtures in my invention may be removed at a labor cost of 20¢ as com- 75 pared with a cost of over \$1 for similar fixtures now generally in use.

Further and more specific objects, features and advantages will more clearly appear from the detail description given below 75 taken in connection with the accompanying drawings which form a part of this specification.

In the drawings:—Figure 1 is a side view of a window having coöperating therewith an arrangement embodying my improvements in their preferred form, certain parts being broken away and shown in section in order to more clearly illustrate the improvements. Fig. 2 is a section taken substantially on a line 2—2 of Fig. 1. Fig. 3 is a section taken substantially on a line 3—3 of Fig. 1. Fig. 4 is a section taken substantially on the line 4—4 of Fig. 1. Fig. 5 is an enlarged detail view of one of the latches partly broken away to more clearly illustrate the same. Fig. 6 is an edge view of the latch shown in Fig. 5. Fig. 7 is a view similar to Fig. 5 but showing a modified form of latch.

Referring to the drawings, 1 represents a glass window fitted in the window sash 2 within a window frame provided with a window seat 3 and side frame members 4, 4. Secured to or forming part of the side members of the window frame are sheet metal members 5, 5, one on each side of the window frame, and each provided with an outer flange 6 forming an outer guide for the sash 7 of an outer window 8. One of the members 5 is clearly shown in Fig. 2, and each is provided with a series of three slots 9, 9, 9 each having a reduced lower end portion 10. Each plate 5 is also provided with a set of three slots 11, 11, 11, each having a re- 110

- duced lower end portion 12, 13, 13 represent rack members provided with a vertical row of rack teeth 14 and a curtain guide groove 15. Formed integral with the back 5 side of these rack members are cleats or keys 16 adapted to be slipped through the slots 9, and then when the racks 13 are dropped downwardly, the cleats engage behind the narrow portions of the slots at 10 and form 10 a wedging fit therewith so as to securely join by a slip joint the rack members 13 to the member 5, but so that they are easily removed therefrom.
- Screwed on to the window sash 2 are 15 plates 17 provided with slots 18 having laterally extending reduced portions 19 (see Figs. 1 and 3). 20, 20 represent latches composed of a front member 21 and a rear member 22 secured together by screws 23 20 and between which is pivoted a latch member 24, having a handle 25 and a projecting end 26 adapted to engage with the rack teeth 14. The latch is provided with cleats or keys 27 integral with the latch member 22 25 which cleats are adapted to be slipped through the large part of slots 18 and then pulled laterally to engage behind the narrow portion of the slots 19 with a wedging fit therein so as to become securely joined by a 30 slip joint to the plates 17, and thereby to the window sash 2, but easily removable therefrom. The latch member 21 may be provided with integral handles 28 and 29. To raise the window it is only necessary to 35 grasp the handles 28 and 29 and lift the window sash, whereupon the latch member 26 will ride over the rack teeth 14, and when the handles 28 and 29 are released the latch member 26 will engage the rack teeth 40 14 to fasten the window in the position desired. To lower the window the handles 25 and 28 are grasped and pressed toward one another whereupon the latch member 26 becomes disengaged from the rack teeth, 45 and the window may be lowered to the position desired. It will be understood that while, in the arrangement shown, provision is made for two latches 20 and two rack members 13, one on each side of the window 50 respectively, nevertheless such fixtures may be provided for one side of the window only, if desired.

In the modification shown in Fig. 7, a modified form of latch 30 is shown provided 55 with similar cleats 27, 27, for engagement with the slots 18 and 19 but having two pivoted members therein. One latch member 31 pivoted at 32 is provided with an end portion 33 for engaging the rack teeth 14, a 60 while another latch member 34 pivoted at 35, and provided with a handle 36 carries on its opposite end a weighted portion 37 having a top cam face for engaging the rear weighted end of the member 31 so that upon 65 pressing down upon the handle 36, the rear

end of member 31 is raised and projection 33 is relatively lowered to disengage it from the rack teeth 13. In both forms of latches the parts are so weighted that they return to their normal position shown in the drawings, by gravity, thus avoiding the use of 70 springs and other movable parts, which are likely to get out of order.

40, 40 represent another set of rack members provided with rack teeth 41, each having integral therewith cleats or keys 42 for engagement with the slots 11, 12, to secure 75 rack members 40 to the member 5, by slip joints in the same manner that the rack members 13 are secured to the member 5 by the 80 cleats 16. The rack members 13 and 40 form front and rear guides for the window sash 2, and the rack members 40 form inner guides for the window sash 7 as clearly shown in Fig. 3. Latches or locks 20 are removably 85 secured to the window sash 7 in the same manner that they are secured to the sash 2, and coöperate with the rack members 40 in the same manner that they coöperate with the rack members 13. In order to prevent 90 the rack members 40 from being pulled or slipped upwardly when the window is raised, thumb screws 50 are provided screw-threaded 95 therein and having end portions 51 engaging holes 52 in the plate or member 5. These screws 50 are not for the purpose of securing the racks 40 to the plate 5, but merely for preventing the rack members 40 from slipping upwardly relative thereto after they have been put into place. The 100 screws 50 are not screw-threaded into the thin metal part 5, but only into the thick portion of rack member 40 so that there is little likelihood of the screw threads thereon becoming unduly worn away. The screws 105 50 are normally hidden from view behind the upper portion of the window frame. In a similar manner the members 13 may be prevented from moving upwardly when the window 1 is raised by means of similar 110 thumb screws 53 coöoperating with holes 54 in the members 5.

It will be noted that the slots 11, 12 are substantially vertical so that there is no danger of the rack or catch member 13 being 115 forced toward the sash, and binding of the sash in this manner is substantially prevented. The restricted portion 19 of the slot 18 being extended away from the rack 13 the latch is practically locked in place by the 120 rack 13 which prevents the latch from moving laterally and becoming disengaged.

In order to remove the parts, the thumb screws 53 are first unscrewed to disengage 125 them from the members 5. The rack members 13 are then pushed upwardly until the cleats 16 come opposite the large part of the slots 9 whereupon they are easily slipped out and the rack members 13 removed entirely. The window 1 with its sash 2 is then easily 130

slipped out of the window frame whereupon the latches 20 are pushed laterally so that the cleats come opposite the large portion of the slots 18 when they may be easily slipped 5 out through the slots and the latches 20 completely removed. Then screws 53 may be unscrewed to disengage them from the members 5 and the rack member 40 may be removed in the same way, and thereupon the 10 window 8 with its sash 7 may be slipped out inwardly in a similar manner. By a reversal of operations, all the parts are easily and quickly replaced in a minimum of time and with great ease. It is unnecessary to 15 remove the members 5 or the members 17 because they are normally hidden from view, and do not require refinishing. Members 5 may form part of the window frame or be secured thereto in any similar manner. In 20 wooden cars they may be screwed to the woodwork. The curtain guide 15 being a part of the rack member 13 is removed simultaneously with it.

While I have described my improvements 25 in great detail and with respect to the preferred form thereof, it will be understood that I do not desire to be limited to such details, since many changes and modifications may be made and the invention embodied in widely different forms without departing from the spirit and scope thereof in its broader aspects.

What I claim as new, and desire to secure by Letters Patent is:

35 1. An arrangement of the class described having in combination with the window frame and sash, a catch member removably joined to the side of the window frame by a key and slot connection, and a latch carried 40 by the sash and positioned to coöperate with the catch member to hold the window in raised position.

2. An arrangement of the class described having in combination with the window 45 frame and sash, a metallic rack member removably joined to the side of the window frame by a key and slot connection, the slot being substantially vertical to prevent the catch member binding the sash, and a latch carried by the sash and positioned to coöperate with the rack member.

50 3. An arrangement of the class described having in combination with the window frame and sash, a catch member removably joined to the side of the window frame by a key and slot connection, a latch carried by the sash and positioned to coöperate with the catch member to hold the window in raised position and a pin for normally preventing vertical movement of the catch member with respect to the window frame.

4. An arrangement of the class described having in combination with the window frame and sash, a catch member removably 55 secured to the side of the window frame by

a key and slot connection and a latch member removably secured to the sash by a key and slot connection and positioned to coöperate with the catch member to hold the window in raised position. 70

5. An arrangement of the class described having in combination with a metallic window frame member and a metallic window sash member, a metallic rack member removably secured to the metallic window 75 frame member by a key and slot connection and a latch removably secured to the metallic window sash member by a key and slot connection and positioned to coöperate with the rack member to hold the window in 80 raised position.

6. An arrangement of the class described having in combination with the window frame and sash a catch member removably joined to the frame by a key and slot connection and removable from the frame by an upward movement thereof, and a latch removably secured to the sash by a key and slot connection, said catch member serving 85 to lock said latch in position on the sash. 90

7. An arrangement of the class described having in combination with the window frame and sash, a metallic rack member removably joined to the side of the window frame by a key and slot connection, and a 95 latch carried by the sash and positioned to coöperate with the rack member, said rack member serving as a guide to retain the sash in position, whereby removal of the rack member permits removal of the sash. 100

8. An arrangement of the class described having in combination with the window frame and sash, a metallic rack member removably joined to the side of the window frame by a key and slot connection, and a 105 latch carried by the sash and positioned to coöperate with the rack member, said rack member having a curtain guide thereon, whereby removal of the rack member also causes removal of the curtain guide. 110

9. An arrangement of the class described having in combination with an inner and an outer window, rack bars carried by the window frame and serving as inner guides for the outer window and outer guides for the inner window, rack bars carried by the window frame and serving as an inner guide for the inner window, and means coöperating with said rack bars for holding the windows in raised position, said rack bars being 115 secured to the window by slip joints. 120

10. An arrangement of the class described having in combination with the window and window frame, a sheet metal member rigid with the window frame having a series of slots with reduced end portions, a catch member provided with cleats adapted to be inserted in said slots and to engage said reduced end portions with a wedging action, to secure the catch member to the frame, and 125 130

means coöperating with said catch member to hold the window in raised position.

11. An arrangement of the class described having in combination with the window frame and sash a catch member secured to the window frame and a latch member co-operating therewith and secured to the sash

by a key and slot connection and removable from the sash by an outward lateral movement thereof.

10

Signed at Albany, in the county of Albany and State of New York, this 22nd day of July, A. D. 1918.

GEARY E. CARSON.
